(57) **CLAIM**

The ornamental design for a putting guide, as shown and described.

DESCRIPTION

FIG. 1 is a perspective view of a putting guide showing a new design;

FIG. 2 is a front view thereof;

FIG. 3 is a rear view thereof;

FIG. 4 is a left side view thereof;

FIG. 5 is a right side view thereof; and,

FIG. 6 is an enlarged view of portion 6 shown in FIG. 1. The broken lines in FIGS. 1 and 6 depict the bounds of the detail view and form no part of the claimed design.

The broken lines in FIG. 4 depict portions of the putting guide and form no part of the claimed design.

1 Claim, 6 Drawing Sheets
